UNITED STATES PATENT OFFICE

102,042

DESIGN FOR A TOY AEROPLANE

David A. Vaughan, Woodstock, N. Y.

Application August 31, 1936, Serial No. 64,657

Term of patent 3½ years

To all whom it may concern:

Be it known that I, David A. Vaughan, a citizen of the United States, residing at Woodstock, in the county of Ulster and State of New York, have invented a new, original, and ornamental Design for Toy Aeroplanes, of which the following is a specification, reference being had to the accompanying drawings, forming part thereof, in which

Fig. 1 is a side elevational view of a toy aeroplane showing my new design;

Fig. 2 is a front elevational view; and

Fig. 3 is a top plan view.

I claim:

The ornamental design for a toy aeroplane, as shown.

DAVID A. VAUGHAN.
